CLAIM

I claim the ornamental design for a device for supporting an object, as shown and described.

DESCRIPTION

FIG. 1 is a perspective view as seen from the front and top side of one embodiment of a device for supporting an object showing the new design;

FIG. 2 is a front elevational view thereof;

FIG. 3 is a rear elevational view thereof;

FIG. 4 is a top view thereof;

FIG. 5 is a bottom view thereof;

FIG. 6 is a perspective view as seen from the front and top side of an alternative embodiment of a device for supporting an object;

FIG. 7 is a front elevational view thereof;

FIG. 8 is a rear elevational view thereof;

FIG. 9 is a top view thereof; and,

FIG. 10 is a bottom view thereof.
